US00D692502S

(12) United States Design Patent
King

(10) Patent No.:

US D692,502 S

(45) Date of Patent:

 Oct. 29, 2013

(54) GAME BOARD

(71) Applicant: innovate! Technologies Group, LLC,
Montgomery, AL (US)

(72) Inventor: Troy Robin King, Montgomery, AL
(US)

(73) Assignee: Innovate! Technologies Group, LLC,
Montgomery, AL (US)

() Term: 14 Years

(21) Appl. No.: 29/436,997

(22) Filed: Nov. 12, 2012

(51) LOC (9) Cl. 21-03
(52) U.S. Cl.

(52) U.S. CR. USPC D21/369; D21/354
(58) Field of Classification Search

(58) Field of Classification Search
USBC D21/351 35

USPC D21/331, 334, 369, 371-373, 383,
D21/396-397; 273/138.1, 141 R, 142 R, 146,
273/268, 274; 463/16-17, 20, 46-47
